(57) **CLAIM**

The ornamental design for a starter pier for pier bracket assembly, as shown and described.

DESCRIPTION

FIG. 1 is a perspective view of a starter pier for pier bracket assembly, in accordance with the first embodiment;

FIG. 2 is a leading end view thereof;

FIG. 3 is a rear end view thereof;

FIG. 4 is a first side view thereof;

FIG. 5 is a second side view thereof;

FIG. 6 is a third side view thereof;

FIG. 7 is a fourth side view thereof;

FIG. 8 is a side view thereof, shown in condition of use;

FIG. 9 is a perspective view of a starter pier for pier bracket assembly, in accordance with the second embodiment;

FIG. 10 is a leading end view thereof;

FIG. 11 is a rear end view thereof;

FIG. 12 is a first side view thereof;

FIG. 13 is a second side view thereof;

FIG. 14 is a third side view thereof;

FIG. 15 is a fourth side view thereof; and,

FIG. 16 is a side view thereof, shown in condition of use.
The claim is shown with a symbolic break in its length. The
appearance of any portion of the article between the break
lines forms not part of the claimed design.

The broken lines in the drawings depict portions of the
starter pier for pier bracket assembly that form no part of the
claimed design. The broken lines showing the pier bracket
assembly in FIGS. 8 and 16 depicts environment that forms
no part of the claimed design.

The surface shading, if any, illustrated in the figures is
provided merely to highlight the contour of the design and
it is not intended to be illustrative of texture or gloss.
